NEEDLE HOLDING SPOOL

Sylvia L. Press, Philadelphia, Pa.

Application September 24, 1937, Serial No. 165,425

3 Claims. (Cl. 223—109)

My invention relates to needle holding spools of fibrous material, such for example, as wood. The object is to provide a thread containing spool with a hole or channel extending longitudinally within the body of the spool between its central bore and its periphery.

This hole or channel is preferably inclined to the plane of spool's end face, and extends entirely through the spool from end to end, or it may extend through one end of the spool to near, but not through the other end.

This hole or channel is adapted to receive a sewing needle, suitable for the thread wound upon the spool.

15 The hole or channel may be of sufficient length to receive the entire length of the needle, which is usually the preferred embodiment.

The channel may have such cross-sectional dimension in a part at least of its longitudinal extension, as to receive the needle with a reasonably close fit so that the needle may be inserted and normally held therein but may be easily withdrawn therefrom.

Various other means may be provided within 25 the channel for normally holding the needle therein, while at the same time permitting its withdrawal therefrom with the application of slight force. In other words the hole or channel may be so formed or dimensioned as to hold the proper needle therein, against accidental displacement, or separate means may be provided within the channel for holding the needle or needles against accidental displacement. The hole or channel may be adapted to hold one needle 30 or a plurality of needles, with suitable means within the hole for preventing their accidental dislodgment. As a means for arbitrarily withdrawing a needle from the hole, the needle is inserted in the hole with a piece of thread attached 35 thereto, the portion of thread which projects from the hole, providing means for withdrawing the needle from the hole.

40 Referring to the drawing which illustrates merely by way of example, suitable embodiments of the invention:

Fig. 1 is an elevation of the needle holding spool.

Fig. 2 is a top view, in plan, of the same.

50 Fig. 3 is a vertical fragmentary section on line 3—3 of Fig. 2.

Figs. 4 and 5 are similar sections on a larger scale, showing modifications.

55 Fig. 6 is a fragmentary section on a still larger scale, to show more clearly the needle gripping means shown in Fig. 5.

Fig. 7 is a view in perspective and part section on the plane of line 3—3 of Fig. 2.

Fig. 8 is a longitudinal section on the same plane indicating the method of partially closing the channel.

Similar numerals refer to similar parts throughout the several views.

In the examples shown in the drawing, 11 represents a spool of thread, having the central bore 12. 13 represents the slightly inclined hole 10 or channel extending longitudinally between said bore 12 and the periphery of the spool. This channel or hole 13 is adapted to receive the needle 14, which is inserted therein and which is preferably provided with a thread 15 attached to 15 the needle 14.

While it may sometimes be desirable to provide the hole or channel 13 of such dimensions as to secure a close fit of the needle therein, this will require a needle within certain size limits, so that 20 it is usually desirable to provide means whereby needles of substantially different sizes may be held by the same spool. That is to say, it is usually preferred to provide the hole 13 of such diameter as to receive one or more needles, and to provide 25 suitable means in combination therewith for securing the needle or needles in the hole or channel against accidental displacement.

In accordance with the arrangement shown in Fig. 4 a magnetized piece 19 of steel, or other 30 suitable material, is forced into or secured in one end of the hole or channel 13. This magnetic piece may be in the form of a resilient loop, so that, when the needle 14, is inserted in the hole or channel 13, it will engage the piece 19, which 35 will act as a magnet, normally to hold the needle in place until sufficient force is applied to overcome said magnetic attraction.

In accordance with the arrangement shown in Fig. 5, a string gripper or clamp 20 is secured in 40 one end opening of channel 13 with outwardly curved contacting lips 21, so arranged that when the needle 14 is inserted into the channel 13, the needle point will enter between said lips 21 and will be held thereby against accidental dislodgment.

It will be understood that various forms of gripper may be used, and the same may be formed to cooperate with the wall of the hole or channel to clamp one or more needles.

50 In accordance with the arrangement shown in Fig. 8, a sharp pointed instrument, such as a center punch 17, is driven into the spool at the top or bottom, or both, adjacent the margin of the hole or channel opening, thereby upsetting 55

the fiber, which is an integral part of the spool, as indicated at 18, and partly closing or obstructing the said opening. Since said fiber is usually soft and yielding, a needle may be pushed easily into the channel 13 past the upset or distorted fiber. Thus, said distorted fiber will effectively prevent the accidental dislodgment of the needle from the channel.

It should also be noted that, in accordance with 10 the arrangement shown in Fig. 8, a wide range of needle sizes, or even a plurality of needles, may be carried by a single channel in the spool, simply by making the hole or channel 13 of sufficient area of cross-section, and by upsetting or distorting 15 a larger area 18 of the fiber adjacent to or surrounding the opening of the hole or channel.

Since however the fiber, as stated, is soft, only a slight external force will be necessary to withdraw the needle from the channel past the distorted fiber.

In this application, the term "integral" is used 20 in its limited sense as applied to mechanical devices. That is, it is used to describe a construction which is all of one piece of material, as contrasted with a construction which is composed of 25 several interconnected pieces of material.

Where the channel 13 extends entirely through 30 the spool and is open at both ends, as shown in Fig. 8, it is usually desirable to partially close the opening at each end as described. The portion 35 of thread 15 which is left in the needle, may be utilized in applying the necessary external force for withdrawing a needle from the spool. The free end or ends of the thread 15 may be secured in the slit 16 which is usually provided in the flange of the spool 11.

It sometimes happens that the needle is longer

than the spool, when it is desirable that the needle should be entirely cased within the spool, for packing and other purposes. For example, in Figs. 1 and 3 the spool is shown as 1½ inches long, while the needle may be over 1½ inches long. In such case the needle may be entirely cased within the spool by making the hole diagonal, extending at both ends into the flange. 5

Obviously a single spool may be provided with more than one hole or channel. 10

What I claim is:—

1. A needle holding spool, having a hole extending longitudinally therein from one end toward the other end between the bore of the spool and its periphery, and a magnetized element secured 15 in said hole for engaging the inserted needle and normally maintaining the same against accidental displacement.

2. A device of the character described, comprising a spool of fibrous material, having a needle 20 receiving channel extending within the spool from one end toward the other end, and between the bore of the spool and its periphery, said channel having projecting therein, a distorted portion of the material forming the main body of the spool 25 for yielding engagement with the needle to prevent its accidental displacement.

3. A device of the character described, comprising a spool of fibrous material, having a needle receiving channel extending within the spool from one end toward the other end, and between the bore of the spool and its periphery, said channel having an integral portion of its wall projecting into said channel to prevent accidental displacement of the needle. 30 35
